8 Claims. (Cl. 158—4)

This invention relates to combustion apparatus for liquid fuel and is particularly applicable to combustion chambers of the kind having an air inlet at one end and an outlet for the products of combustion at the other, and including primary and secondary zones which communicate with one another at their adjacent ends, fuel being injected into the primary zone and the flow through the two zones being such that a proportion of the products of combustion and unburnt air flow continuously from the outlet end of the secondary zone through the primary zone to the inlet end of the secondary zone, where fresh air also enters the secondary zone, whereby the fuel is injected into a mixture of air and combustion products in the primary zone so as to tend to be vaporized before entering the secondary zone. Such a combustion chamber is shown in the present applicant's U.S. Patent Serial No. 2,882,843.

According to the present invention combustion apparatus for liquid fuel comprises a tubular combustion chamber of the kind set forth, including rotary impeller means arranged between the primary and secondary zones which controls the gas flow through the primary zone and into the secondary zone, and a centrifugal rotary fuel distributing device arranged to distribute fuel into the primary zone and which is rotated with the impeller means.

The two zones are preferably separated by a wall concentric with a rotary distributing part of the centrifugal rotary fuel distributing device and the rotary impeller means comprises a rotor having impeller blades which are arranged to rotate with said rotary distributing part and which lies adjacent to the outlet of the primary zone defined by the end of the wall which separates the two zones through which gas flows into the inlet end of the secondary zone from the adjacent end of the primary zone.

Control apparatus may be included for varying the rate of flow of fuel delivered by the centrifugal rotary fuel distribution device and the volumetric rate of flow of gas from the primary to the secondary zones in synchronism for a given speed of rotation, and in a preferred arrangement the apparatus for varying the volumetric rate of flow to the secondary zone from the primary zone acts to move the impeller rotor axially in relation to the outlet from the primary zone defined by the end of the wall separating the two zones.

In a convenient arrangement the centrifugal rotary fuel distributing device includes liquid metering apparatus of the kind wherein the liquid rises up the sides of a rotatable vertical tube.

If such apparatus is used then the impeller rotor may be connected to the rotatable vertical tube of the liquid metering apparatus, and the rotary distributing part of the rotary fuel distributing device may be in the form of a plate or disc of perforated metal secured in axial alignment to the upper end of the rotatable vertical tube. The arrangement is conveniently such that axial movement of the impeller rotor moves the blades relative to the outlet from the primary zone so that they cause more or less gas to be recirculated, that is to say drawn through the outlet from the primary zone and discharged to the secondary zone.

2

Preferably the control apparatus acts to move the rotatable tube axially relative to the outlet of the primary zone and also acts to cause axial movement of the inner control spill pipe of the liquid metering apparatus to vary the rate of fuel delivery in a predetermined manner.

Second impeller means coaxial with the impeller means referred to above may also be included which act to control the flow of fresh combustion air from the atmosphere into the inlet end of the secondary zone.

This second impeller may in this case comprise a rotor having impeller blades situated below and connected to the first impeller rotor.

The invention may be performed in various ways but one embodiment including a centrifugal rotary fuel distributing device including liquid metering apparatus will now be described by way of example. The accompanying drawing shows in detail a cross-section of the liquid fuel burner apparatus.

The combustion apparatus to be described is for use with a small waterboiler of a domestic hot water or central heating system. The combustion chamber is of annular form and comprises an outer cup like shell indicated generally at 1 the upper end of which is open and the lower end of which is formed with a large diameter intake bore 2 through which combustion air to be burnt in the combustion chamber can be drawn in the direction of the gas flow being indicated by arrows A. The shell 1 comprises a cylindrical outer part 3 to which is rigidly attached a dished inner part 4 which forms the lower part of the shell, the cylindrical outer part 3 having a downward extension or skirt 5 which serves to support the cup like shell 1 from a horizontal bed plate 6 to which it is secured. Arranged concentrically within and secured to the outer part 3 is a frusto-conical baffle 7 the wider upper end of which is connected to the upper periphery of the part 3 while its lower end is connected to an annular baffle ring 8 spaced from the part 4 by supports (not shown) to provide a tapering air passage 10 between the frusto-conical baffle 7 and the part 4, into which passage 10 a proportion of the incoming combustion air can be diverted, the remainder passing into the combustion space 11 through the ring 8. The frusto-conical baffle 7 is provided with a series of holes 12 through which air passing through the passage 10 between the baffle and the outer shell can also enter the combustion space 11. The annular baffle ring 8 is displaced upwardly somewhat from the lower end of the part 4 and an annular cup shaped deflector 13 of smaller diameter is positioned slightly lower than the baffle ring 8 and overlaps this baffle ring 8 to ensure that combustion air entering through the large diameter intake port 2 passes upwards through the space between the annular deflector 13 and the part 4 and is divided by the annular baffle ring 8 into two streams one of which enters the tapering air passage 10 while the other enters the combustion space 11 directly through the annular space between the annular deflector 13 and the annular baffle ring 8 as set forth above. An annular wall 14 is provided within the combustion space 11 which is maintained coaxially by tangential supports 15 extending between it and the annular baffle 13. The lower end of the wall 14 is formed with an inwardly extending flange 16, and the outer diameter of the wall is somewhat greater than the diameter of the air intake bore 2. The bore defined by the internal flange 16 provides an outlet passage 17 from the space 18 defined within the wall.

A centrifugal rotary fuel distributing device 20 is arranged to rotate within the space defined by the annular wall 14 and includes liquid fuel metering apparatus comprising a liquid reservoir 21 which is secured beneath the bed plate 6 and which incorporates a fuel level control device 22 of the type used in a conventional carburetor,

to control a fuel inlet port 23, so that fuel is maintained at an approximately constant level in the reservoir 21. A flow metering device in the form of a tubular assembly extends vertically from this chamber through a bore 23 in the bed plate 6 and comprises a rotatable vertical tube referred to herein as the outer pipe 24 which is of circular cross-section and the lower part of which, referred to herein as the fuel pipe 25, is of constant diameter and vertically supported to rotate as hereinafter described, while its upper part, referred to herein as the outlet tube 28, is in the form of an inverted conical frustum, the lower end of which merges smoothly into the upper end of the fuel pipe 25, while its upper end is open and forms a mouth constituting an outlet opening 30 outwardly flared to constitute at its termination a horizontal lip 31. The outer pipe 24, 25 is surrounded by and rigid with a co-axial tubular casing 32 which also extends into the reservoir 21 through the bore 23 in the bed plate 6 and which is connected to the outer pipe 24, 25 by a flange 55 at an intermediate point and at its upper end. A sealing gland 33 surrounds the casing 32 where it passes through the bed plate 6 to prevent the escape of fuel from the reservoir 21. The assembly comprising the outer pipe 24, 25 and the tubular casing 32 is rotatably supported on upper and lower spaced bearings 26, 27 carried at the upper and lower ends of a vertical hollow stanchion 34 which is supported by a spider 35 in the form of a cylindrical member coaxial with the stanchion and secured at its upper end beneath the bed plate 6 while its lower end carries spacers 36 which are connected to the lower end of the stanchion 34 so that it passes coaxially through the bore 23 in the bed plate 6.

The stanchion 34 thus surrounds the fuel pipe 25 and is surrounded by the lower end of the casing 32 the bearing 26 at the upper end of the stanchion 34 having an outer bearing surface so that it bears against the inner surface of the casing 32 and the lower bearing 27 having an inner bearing surface engaging the outer lower end of the fuel pipe 25. The outer pipe 24 together with its outer casing 32 can be rotated at a constant speed about its axis by an electric motor (not shown) mounted adjacent to the reservoir 21 and driving the casing 32 and pipe 24 through a flat belt 37 acting on a pulley 38 formed on the outside of the casing 32 where it surrounds the upper bearing 26. A space is left between the pulley 38 and the casing 32 to form an annular pulley cooling chamber 39 through which fuel can be passed to cool the pulley as hereinafter described.

Mounted concentrically within the fuel pipe 25 is a non-rotating vertically extending and vertically movable spill or overflow pipe 40 the upper end 41 of which extends into the frusto-conical outlet tube 28, and the lower end of which protrudes beyond the lower end of the fuel pipe 25 where it is secured to one end of a horizontally extending rigid link 42 the other end of which is adjustably connected to a vertically extending movable control rod 43 which can be moved to adjust the height of the upper end 41 of the spill pipe 40 within the outlet tube 28. The upper end of this control rod 43 is pivoted to one end of a lever 44 which is itself pivoted at an intermediate point 45 to a support 46 attached to the upper surface of the bed plate 6 and the other end of which is connected to the operating rod 47 of control apparatus, either manual as shown or some automatic device, for example a thermostat. The arrangement is such that movement of the crank lever 44 about its intermediate pivot point 45 causes the spill pipe 40 to be raised or lowered. Where the control rod 43 passes through the base plate a sealing gland is provided to prevent the escape of fuel from the fuel chamber 21. The upper part of the rod 43 has been omitted from the drawing in order that further apparatus which is in line with it, and which is to be described, can be seen.

The spill pipe 40 is located coaxially within the fuel pipe 24 by a helical member 50 which extends along and

is secured to the outer surface of the spill pipe 40, a small working clearance being provided between the helical member 50 and the inner surface of the fuel pipe 25. The helical member 50 thus provides, between the lower halves of the fuel pipe 25 and the spill pipe 40 a helical passage the outer surface of which is formed by the rotatable fuel pipe 25 so that fuel is drawn upwards by frictional drag from the reservoir 21 towards and into the outlet tube 28. A pair of transverse bores 51 are also provided in the wall of the fuel pipe 25 where it merges into the frusto-conical outlet tube 28 through which there is a constant fuel bleed into a chamber 39a and thence to the annular pulley cooling chamber 39 through apertures 52 and out of this chamber through openings 53 and hence back to the reservoir 21 by way of an annular cooling passage 54 defined by the space between the lower part of the outer casing 32 and the stanchion 34. Fuel from the chamber 39a also lubricates the bearing 26 and then flows down a passage 54 to lubricate a thrust race 56 hereinafter again referred to in addition to flowing down a passage between the stanchion 34 and the fuel pipe 25 to lubricate the bearing 27.

The lower end of the casing 32 is provided with holes by which the fuel can escape from its lower end via the thrust race 56 into the reservoir, this thrust race being supported by a flanged horizontal plate 57. The plate 57 is connected by a member 58 to a vertically extending rod 60 which passes through the base plate 6, sealing means 61 being provided to prevent the escape of fuel from the main fuel chamber 21. The rod 60 is in line with the rod 43 in the drawing, and the upper part of the rod 43 has therefore been omitted in order that the rod 60 can be more clearly shown. The upper end of the rod 60 is pivotally connected to a lever 62 which is pivoted at an intermediate point 63 to a support 64 connected to the base plate 6 so that the movement of the lever 62 about its intermediate pivot point 63 causes the outer casing 32 together with its associated outer pipe 24 to move vertically. The other end of this lever 62, is connected to the operating rod 47 of the control apparatus at the same point as the lever 44 for moving the overflow pipe 40, but the distance from the intermediate pivot point 63 is greater than that from the pivot point 45 of the other lever 44 so that as the outer casing 32 is moved vertically downward the overflow pipe 40 also moves downward but to a further extent so that the flow of fuel is reduced, the apparatus working in a similar but opposite manner when the movement is reversed.

The length of the pulley 38 is such that it allows the flat driving belt 37 to move up and down to allow for the different vertical positions of the pulley 38 when the casing 32 is moved and to allow the belt 37 to remain radially in line with the upper bearing 26.

An impeller device is connected to the outer casing 32 the rotor of which impeller comprises a pair of annular discs 65, 66 vertically spaced from one another along the length of the casing the lower disc 66 having an upwardly extending flange 67 the rim of which is connected to the upper disc 65 at its outer periphery, so that the discs define an annular rotor cooling chamber 68 between them. A ring of impeller blades 70 is secured to the upper surface of the upper disc 65 and a similar ring of impeller blades 71 are secured to the lower surface of the lower disc 66, an annular baffle plate 72 being connected to the lower edges of the lower ring of blades 71 so that an annular space, referred to herein as the intake orifice 73, is left between the outer casing 32 and the inner edge of the annular disc 72 which is turned downwards to form a flange which defines the intake port 2. The rotor and its associated impeller blades 70, 71 are so vertically disposed and dimensioned that when the outer casing 32 is in its highest vertical position the annular baffle plate 72 connected to the lower ring of impeller blades 71 is substantially in line with the intake port 2. Similarly the lower disc 66 of the rotor to which the lower ring of im-

eller blades 71 is connected is substantially in line with the lower end of the annular deflector 13 and the upper ring of impeller blades 70 is immediately beneath the inturned flange 16 of the annular wall 14, so that when the impeller is rotated air will be drawn by the blades 71 through the annular intake orifice 73 opening from the intake port 2 and delivered into the space between the annular deflector 13 and the shell 1 and hence into the space 11 both directly through the passage between the parts 8 and 13 and through the space 10, as indicated by the arrows A. At the same time there will be a gas flow, induced by the blades 70, from the space 11 into the upper end of the space 18 out of the lower end of this space and into the space 11 between the parts 16 and 13, as indicated by the arrows B. Holes 74 and 76 are provided in the casing 32 and holes 77 in the plate 66 so that air will be circulated through a cooling space 75 between the casing 32 and the part 28 above the pulley 38 and through the annular rotor cooling space 68 defined within the rotor, by reason of centrifugal force exerted on the air during rotation in the annular space 68.

The upper end of the outlet tube 28 is arranged to lie at an appropriate point within the inner wall 14 and the rotary distributing part of the centrifugal rotary fuel distributing device is in the form of a plate or disc 78 of perforated metal, for example expanded metal, secured in axial alignment with the upper end of the outer tube 28 so that the liquid fuel will pass through the perforations and will be flung outwardly from the plate or disc 78 when the casing and outer tube are rotated. A small dome-shaped disc 80 is connected to the plate or disc 78 so that fuel only passes through the perforations in an annular space 81 between the upper end of the outer tube 28 and the dome-shaped disc 80.

The combustion chamber is of the type having primary and secondary zones. The primary zone is the space 18 within the annular wall 14 and the secondary zone is the space 11 between the annular wall 14 and the frusto-conical baffle 7. In operation fuel is delivered by the disc 78 into the primary zone 18 in which, as explained above, the flow is downwardly, and the fluid consists of a mixture of air, burning products of combustion and unburnt fuel. This mixture then flows through the passage 17 between the inturned flange 16 and the casing 32, radially outwards between the upper impeller blades 70 and into the secondary zone 11 where the mixture of fuel and gases mingle with additional combustion air drawn in through the intake orifice 2 by the lower blades 71 of the rotor. A further part of the total combustion air is delivered into the secondary zone 11 after passing through the tapered passage 10 and the holes 12 in the frusto-conical baffle 7 while the combustion products are finally exhausted through the open upper end of the combustion space 11. There is thus a constant recirculation of part of the burning products down through the part 11 and it is into these burning products that the fuel is delivered, thus tending to vaporize the fuel before it reaches the zone 11.

When the electric motor is started it rotates the casing 32 causing the impeller rotor to rotate and thus create the necessary flow of combustion air into the combustion chamber as a whole and the re-circulation flow within that chamber itself. It also causes fuel to be drawn up the helical passage defined by the helical member 50 and delivered through the annular space between the upper ends of the fuel pipe 28 and the overflow pipe 40 to the interior of the outlet tube 28. The fuel within the outlet tube 28 tends to rise up the inner wall of the tube so that the surface of the fuel is in the general form of a concave meniscus, having its center at the upper end 41 of the spill pipe 40 so that the level of the meniscus is determined by the level of the upper end 41 of the overflow pipe 40. The outermost and highest part of the meniscus extends to the upper end of the outlet tube 28 where the fuel is flung radially outwards across the perforated plate or disc

78 and into the primary zone of the combustion chamber by centrifugal force where it is initially ignited by suitable means (not shown).

The rate at which the fuel is delivered by centrifugal force from the upper end of the fuel pipe 28 thus depends upon the speed of rotation and upon the vertical position of the upper end 41 of the overflow tube 40 which controls the level of the fuel in the outlet tube 28.

The spiral member 50 is thus so designed that its pumping action is sufficient to supply fuel continuously to the outlet tube 28 at least equal to and preferably greater than the maximum rate that fuel is required to flow out of the outlet tube 28 in addition to providing a sufficient flow of fuel through the transverse bores 51 in the fuel pipe 28 to provide the necessary cooling flow behind the pulley 38 and the outer casing and to lubricate the bearings 26, 27 excess fuel flowing down the overflow tube 40.

It will be appreciated that if the overflow tube 40 is raised, the vertical position of the central, lowest part of the fuel meniscus in the outlet tube 28 rises correspondingly, and the rate at which fuel is flung out of the outlet tube 28 increases while the flow of excess fuel into the overflow pipe 40 decreases. If the overflow pipe 40 is lowered, the vertical position of the central, lowest part of the fuel meniscus drops correspondingly, the rate at which fuel is flung out of the outlet tube 28 decreases, and the flow of excess fuel into the overflow pipe 40 increases. Thus the rate of delivery of fuel into the combustion chamber is independent of the precise rate of delivery of fuel by the spiral member 50.

When maximum heat is required from the combustion chamber the overflow tube 40 will be in its uppermost position as will the outer casing 32 to which the impeller rotor is connected so that there is a maximum flow of combustion air into and within the combustion chamber to supply the necessary flow required for the maximum fuel distribution conditions.

If the heating requirement is reduced the outer casing 32 including the impeller rotor 15 moved downwardly away from the combustion chamber so that the upper impeller blades 70 move away from the inturned flange 16 of the inner wall 14 rendering them less effective and producing a reduced reversed gas flow through the primary zone inside the inner wall 14. At the same time the lower impeller blades 71 similarly move out of alignment with the annular space between the annular deflector 13 and the outer shell 1 so that they draw less combustion air into the combustion chamber. The overflow pipe 40 is simultaneously lowered to an even greater extent than the outer pipe 28 so that the fuel flow is also reduced. The arrangement is such that when the outer casing 32 and its associated rotor are in their lowermost positions the lower impeller blades 71 are clear of the outer shell 1 so that there is no induced flow into the combustion chamber of combustion air, and the upper impeller blades are sufficiently far away from the lower flange 16 of the inner wall 14 for their effect to be so considerably reduced as to be almost negligible. In these conditions the flame in the combustion chamber is reduced to a small annular ring on the perforated disc 78 close to the upper end of the fuel pipe 28 where the fuel continues to burn whilst creating very little heat in the combustion chamber.

It will be appreciated that a small flame of the type described above may be allowed to burn for a very great length of time with only a small consumption of fuel and that if heat is required from the combustion chamber it is immediately available merely by operating the member 47 to move the outer casing 32 together with its associated rotor and the spill pipe 40 upwardly to the appropriate position. When such a device is employed with a domestic boiler the member 47 can be connected to a thermostat so that the heat generated in the combustion chamber can be varied to keep the water in the boiler at a desired temperature.

What I claim as my invention and desire to secure by Letters Patent is:

1. Combustion apparatus comprising a combustion chamber of open-ended tubular form having an air inlet at one end and an outlet for the products of combustion at its other end, an annular dividing wall arranged coaxially within the combustion chamber and dividing it into an outer annular secondary zone and an inner primary zone which communicate with one another at their adjacent ends, a rotary fuel distributing device arranged to distribute fuel into said primary zone, control means operative to vary the rate of flow of fuel delivered by said rotary fuel distributing device and the volumetric rate of fluid flow from said primary zone to said secondary zone, effected in the same sense and in synchronism, and rotary combustion-product impeller means arranged between said primary and secondary zones and comprising impeller blades which are operatively arranged to rotate with said rotary fuel distributing device and which lie adjacent to the end of said annular wall adjacent to said air inlet to cause a proportion of the products of combustion and unburnt air to flow continuously from the end of the secondary zone which lies adjacent to the said outlet for the products of combustion through the primary zone to the end of said secondary zone which lies adjacent to the said air inlet and where, therefore, fresh air from the air inlet also enters said secondary zone.

2. Combustion apparatus as claimed in claim 1 in which said control means moves said rotary combustion-product impeller means axially in relation to the adjacent end of said annular wall.

3. Combustion apparatus as claimed in claim 2 including air impeller means coaxial with said combustion-product impeller means and operatively controlling the flow of combustion air from the atmosphere into the end of said secondary zone adjacent to said air inlet in accordance with speed of rotation.

4. Combustion apparatus as claimed in claim 3 in which said air impeller means comprises impeller blades situated below and attached to the said combustion-product impeller means.

5. Combustion apparatus comprising a combustion chamber of open-ended tubular form having an air inlet at one end and an outlet for the products of combustion at its other end, an annular dividing wall arranged coaxially within the combustion chamber and dividing it into an outer annular secondary zone and an inner primary zone which communicate with one another at their adjacent ends, a rotary fuel distributing device comprising fuel metering means comprising a tube, means vertically supporting said tube for rotation about its longitudinal axis, fuel delivery means supplying fuel to the interior of said tube, driving means for rotating said tube, and a control device controlling the rate of fuel ejection from the upper end of said tube when said tube is rotated, said control device comprising a spill device having a spill pipe arranged with its inlet adjacent to the axis of rotation of said tube and thus determining the level of fuel within said tube at the axis of said tube, said device arranged to distribute fuel into said primary zone and rotary combustion-product impeller means arranged between said primary and secondary zones and comprising impeller blades which are operatively arranged to rotate with said rotary fuel distributing device and which lie adjacent to the end of said annular wall adjacent to said air inlet to cause a proportion of the products of combustion and unburnt air to flow continuously from the end of the secondary zone

which lies adjacent to the said outlet for the products of combustion through the primary zone to the end of said secondary zone which lies adjacent to the said air inlet and where, therefore, fresh air from the air inlet also enters said secondary zone.

6. Combustion apparatus as claimed in claim 5 in which said combustion-product impeller means is attached to said rotatable tube of said metering means and rotates therewith.

7. Combustion apparatus as claimed in claim 6 wherein, in said spill device said spill pipe is mounted for vertical adjustment within said rotatable tube to vary the fuel level maintained in said rotatable tube and including control means operatively connected to said spill pipe and to said combustion-product impeller means to vary simultaneously the vertical position to said spill pipe and the vertical position of said combustion-product impeller means relatively to the adjacent end of said annular wall to vary the flow of combustion products through said combustion-product impeller means.

8. Combustion apparatus comprising a tubular combustion chamber having an air inlet at one end and an outlet for the products of combustion at its other end, an annular dividing wall arranged within and coaxially with the combustion chamber to divide it into an outer annular secondary zone and an inner primary zone which communicate with one another at their adjacent ends, a rotary fuel distributing device arranged in said primary zone and comprising a fuel delivery tube vertically mounted for rotation about its axis and having an open upper end, fuel delivery means which supply fuel to the lower end of said tube, driving apparatus which rotates said tube, a spill tube disposed within said device and mounted for vertical adjustment therein to vary the level of fuel maintained in said tube, a perforated rotary distributing plate secured to the upper end of said rotatable tube, combustion-product impeller means rotatable with said rotatable tube and causing a proportion of the products of combustion and unburnt air to flow continuously from the said primary zone into the end of said secondary zone adjacent to said air inlet and air impeller means rotatable with said rotatable tube delivering fresh air from the said air inlet into the adjacent end of said secondary zone.
